(57) **CLAIM**

The ornamental design for a mop refill container as shown and described.

DESCRIPTION

FIG. 1 is a perspective view of a mop refill container showing the new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6. is a top plan view thereof; and,

FIG. 7 is a bottom plan view thereof.

The broken lines in the drawings depict portions of the mop refill container that form no part of the claimed design.

1 Claim, 6 Drawing Sheets
